MANUFACTURE OF SHOES

Walter I. Gillette and Albert W. Dusseault, Haverhill, Mass., assignors to United Shoe Machinery Corporation, Paterson, N. J., a corporation of New Jersey

Application November 5, 1935, Serial No. 48,346

6 Claims. (Cl. 36—11.5)

This invention relates to improvements in the manufacture of shoes and is herein illustrated with particular reference to its application to the manufacture of so-called cross-strap sandals.

5 A cross-strap sandal as ordinarily constructed comprises a sole and a plurality of cross-straps, the latter being secured at their opposite ends to the sole and being adapted to extend over portions of the foot so as to retain the sandal 10 on the foot. As a sandal of this type is worn the movements of the foot impose more or less severe strains upon the localities where the ends of the straps are secured to the sole and, although various expedients have been adopted for holding the 15 strap ends in place, the holding means is quite likely to give way at those points which are subjected to the greatest strains.

Objects of the present invention are to overcome the above-mentioned inherent weakness in 20 the construction of strap sandals and to provide other improvements in the manufacture of shoes and sandals.

With the above objects in view, the invention in one aspect provides a method of making sandals which, as herein exemplified, involves the 25 passing of successive portions of a continuous strip of cross-strap material in crosswise directions above and beneath a sole from one lateral edge portion of the sole to the other, thereby 30 providing an integrally connected series of cross-strap loops for holding the sole on a foot. This method may advantageously be practiced by passing or winding a continuous strip several times over a sole member, for example an insole, on a 35 last, the insole preferably having formed therein a series of marginal openings for receiving the strip as it is being applied and thus determining the locations of the various turns or loops of the strip which are to take the place of the separate 40 cross-straps of a sandal of the usual construction. As illustrated herein a single strip may be employed to provide a series of integrally connected cross-strap loops in the forepart of a sandal while another strip may be employed to 45 constitute an integrally connected series of loops or straps in the heel portion of the sandal, or, if desired, the loops or strips in both the foreparts and heel portions of the sandal may be formed as integral portions of a single strip. Advantageously 50 the ends of the one or more strips employed in the construction of the cross-strap loops will be located at points where the loop structure will be subjected to the least strain, the arrangement at all events being such that the ends of the strip 55 will not be located in the vicinity of the ball line

or in the vicinity of the heel breast line where the strains are the greatest. As illustrated, the arrangement of the strip at the heel portion of the sandal may advantageously be such that the ends of the strip will be located above the sole, 5 where they may be adapted to serve as ankle straps.

The invention consists in the various improvements in the art of making sandals and in the various improved features of sandal construction 10 hereinafter described and specifically pointed out in the claims.

The invention will be explained with reference to the accompanying drawings, in which

Fig. 1 is a perspective view of an insole prepared 15 for use in making a strap sandal;

Fig. 2 is a fragmentary perspective view of an insole showing it prepared in a different way, and illustrating a modification of the manner of preparing it for use in making a sandal;

Fig. 3 is a fragmentary perspective view of an 20 insole, illustrating a further modification in the manner of preparing it for use in making a sandal;

Fig. 4 is a perspective view of a sandal in 25 course of construction;

Fig. 5 is a perspective view of a completed sandal;

Fig. 6 is a cross-sectional view taken substantially along the line VI—VI of Fig. 4;

Fig. 7 is a fragmentary cross-sectional view 30 of a sandal in which the outsole is attached by means of Goodyear stitching;

Fig. 8 is a similar cross-sectional view of a sandal in which the outsole is attached by means 35 of through-and-through stitching; and

Figs. 9 and 10 are perspective views of sandals 40 of modified construction.

In practicing our improved method of making sandals, as exemplified in Figs. 1, 4, 5 and 6, an insole 14 is cut to a desired marginal contour, for 45 example, by means of a clicking die and, in order to prepare the insole to receive the cross-straps, a plurality of elongated marginal openings or slots 16 (Fig. 1) are provided in its forepart and a plurality of similar marginal openings or slots 45 18 are provided in the heel portion of the insole. The slots 16 and 18 may be formed in any suitable manner, for example, by means of punches carried by the clicking die. As indicated at 20 in Fig. 4, the marginal portion of its outer surface is roughed to prepare it for the cement attachment 50 of an outsole thereto. The slotted insole 14 is temporarily secured to the bottom of a last 22, as by means of tacks, one of which is shown at 24. In making the sandal shown in Figs. 4 55

and 5, the cross-straps at the forepart are formed as portions of a single continuous strip or ribbon 26 of suitable cross-strap material while the cross-strapping in the heel portion of the sandal 5 is formed from another continuous strip 28 of the same material as the strip 26. While each of the strips 26 and 28 is shown as being in the form of a ribbon, it need not be of such shape and might, for example, be round in cross-section, in 10 which case round holes would be formed in the insoles for receiving the strips.

In applying the strip 26, as exemplified in Figs. 4 and 5, one end of the strip is temporarily secured to the bottom or outer surface of the insole 15 14 substantially in the central portion of its forepart by any convenient means, such as the tack 30. The strip 26 is then threaded through the adjacent slot 16a in the insole, tensioned over the upper portion of the last 22, passed through 20 the slot 16b and across the bottom of the insole in the vicinity of the ball line and threaded through the slot 16c. Thence the strip 26 is tensioned again over the upper portion of the last, after which it is passed through the slot 25 16d, across the bottom of the insole, through slot 16e, and again over the last. The strip 26 thence passes through the slot 16f, across the bottom of the insole, through slot 16g, over the last, through slot 16h, and thence part way across the 30 insole to the point where its trailing end is temporarily secured to the insole by the tack 32. The strip 26 has thus been passed four times over the last, thereby providing four cross-strap 35 loops 34 which vary in length as determined by the shape of the last and which are formed as integral portions of a single continuous strip, instead of being formed as separate straps each independently secured at its opposite ends to the sole of the sandal as in the usual prior art construction. Those portions 36 of the strip 26 which extend across the bottom of the insole connect the cross-strap portions or loops 34 in such a manner that the latter cannot be pulled loose from the insole, there being no ends save only 40 45 those at the beginning and ending of the strip.

At the heel end of the sandal the manner of application of the strip 28 may differ from that of the strip 26 at the forepart, first, in that the opposite ends of the strip 28, instead of being located beneath the insole, are located above the sole to serve as ankle straps for the sandal. In applying the strip 28 one end portion 40, after having been first temporarily secured by means of a tack 42 to the outer side of the heel portion of the last, is passed rearwardly around the heel end of the last and through the slot 18a, thence across the bottom of the insole, and through the slot 18b. Thence the strip 28 is looped at 44 over that portion of the strip which 50 is held to the side of the last by the tack 42, thence downwardly through slot 18c, across the bottom of the insole and upwardly through slot 18d. Thence the strip is laid in the form of a loop 48 close to the inner side of the last, and 55 thereafter it is passed downwardly through slot 18e, across the bottom of the insole, through slot 18f, around the heel end of the last, and finally it is passed through the loop 48, and around the cone of the last to a point where 60 its trailing end 48 is adapted by means of a series of holes 58 to be engaged by a buckle 52 which is secured to the opposite end portion 40 of the strip and thus to cooperate with the portion 40 to constitute an ankle strap.

75 Thus, the cross-strapping in the heel portion

of the sandal, as well as at the forepart, consists of a continuous strip which is passed alternately back and forth above and below the insole as it is being wound around the insole and the last. At the heel end of the sandal there are no end 5 portions of the cross-strapping located beneath the insole and consequently there are no portions which can pull out or give way while the sandal is being worn. It will be noted that the cross-stretches 36 and 56 of the strips 26 and 28, 10 respectively, serve to hold the cross-strapping securely in place in the vicinities of the ball line and the heel breast line where the cross-strapping is subjected to the greatest strains when the sandal is on the foot.

The strips 26 and 28 having been applied as above described, the usual shank stiffener 58 is laid upon the insole, the opposite end portions of the stiffener being inserted beneath the cross-stretches 36 and 56 of the strips 26 and 28 (Fig. 20 4), whereby the stiffener is effectively held against accidental displacement prior to the completion of the shoe and the ends of the stiffener are prevented from rubbing against the outsole in a manner to cause squeaking when the 25 shoe is being worn. A coating of cement, conventionally indicated at 60, is next applied to the roughened marginal portion of the insole. If, as in the present instance, the outsole is to be cement-attached to the insole, pyroxylin cement 30 may be used and the latter may conveniently be applied by means of a brush, as indicated at 62. More advantageously, however, the cement may be applied by means of a shoe bottom cementing machine, such for example as that disclosed in a copending application for United States Letters Patent, Serial No. 754,648, filed November 24, 1934, in the name of W. L. MacKenzie. The cement as applied to the insole will cover the opposite end portions of the 40 cross-stretches of the strips 26 and 28 which extend across the bottom of the insole and will fill in the slots around those portions of the strips which extend therethrough, as indicated at 64 in Fig. 7, and thus, after the cement has 45 become set, the portions of the strips which are located in the vicinity of the slots will be attached to the insole and securely held in place. The tacks which secure the insole to the last and the tacks 30 and 32 which temporarily secured 50 in place the opposite ends of the strip 26 are removed before the outsole is applied.

The outsole 65 is prepared for cement attachment to the insole in the usual way by roughing its marginal portion and applying cement there- 55 to. Advantageously, the roughened margins of a quantity of outsoles may be pre cemented and as each outsole is to be used the dried cement thereon may be activated by means of a solvent which may be applied by means of a brush or 60 more advantageously by means of a solvent applying machine, such for example as that disclosed in a copending application for United States Letters Patent, Serial No. 692,307, filed October 5, 1933, in the name of C. A. Newhall, 65 now Patent Number 2,042,479, granted June 2, 1936. After the outsole has been laid in place it is held against the bottom of the sandal under pressure by means of a suitable press until the attaching cement has set. Before the attach- 70 ment of the outsole it may be found desirable to apply a suitable filler to the forepart of the insole, as indicated by dotted lines at 66 in Fig. 4. After the outsole has been attached the last is removed, a heel 68 is attached and a suitable 75

sock lining 10 is applied to the upper surface of the insole.

In addition to being attached by means of cement the outsole 65 may also be secured to the insole by means of Goodyear stitching, as indicated at 72 in Fig. 7. Ordinarily, however, when such stitching is to be used, no pyroxylin cement will be employed between the soles, but the outsole will be temporarily held in place by means of 10 rubber cement or latex, care being taken to see that the rubber cement covers at least the opposite end portions of the cross-stretches of the straps 26 and 28 which extend across the insole so as to assist in holding these straps in place. 15 Also, as indicated in Fig. 8, the outsole may be attached to the insole by means of through-and-through stitches 13 such, for example, as lock stitches or chain stitches.

The insole may be provided with open notches 20 17 (Fig. 2) in its edge portions for receiving the cross-straps instead of closed openings such as the slots 16 already described. The provision of open notches, such as the notches 17, is advantageous in that it enables the cross-stripping to 25 be wound around the last and insole without having to be threaded through openings in the insole.

Alternatively, as illustrated in Fig. 8, the cross-straps may merely be passed over the edge of 30 the insole, in which case no notches, slots or other openings need be provided. In cases where no openings of any sort are provided for receiving the cross-stripping suitable marks may 35 be made, if desired, upon the insole, as indicated at 19 in Fig. 3, to indicate the points where the stripping should cross the edges of the insole in order to insure proper location of the cross-straps.

Obviously, the slots, notches or other openings 40 in the insole, or the strap-locating marks thereon, may be so arranged and the strips may be so applied that various arrangements of the cross-straps may be provided and the latter may be interlaced as desired to vary the designs of patterns of the cross-strapping. Thus, portions of 45 the cross-straps which extend across one another above the insole may be secured together, either fixedly by means of rivets, stitches or the like, as indicated at 14 in Fig. 5, or adjustably as, 50 for example, by means of slide buckles, as indicated at 76 in the forepart of the sandal.

The child's sandals shown in Figs. 9 and 10 embody modifications of the above-described arrangement of cross-strapping, Fig. 9 showing the 55 opposite end portions of the strip which constitutes the cross-strapping located between the soles of the sandal. In the construction shown in Fig. 9, in order to provide for removably securing the heel portion of the sandal on the foot, 60 a separate ankle strap is provided in the form of a flexible lacing 78 which, as shown, is tied at 79 to one of the side loops of the heel strapping and is adapted to be tied to the opposite side loop of the heel strapping after the sandal has 65 been placed upon the foot.

In the construction shown in Fig. 10 a single continuous strip constitutes the cross-strapping at both the forepart and heel portion of the sandal. As shown therein, one end of the strip 70 is secured at 80 to the bottom of the insole 140, thence the strip is passed upwardly through a slot in the insole and across the last to form the forepart strap 82, thence across the bottom of the shank portion of the insole at 84, after which 75 it is manipulated to provide the cross-strapping

86 at the heel portion of the last. The strip thence extends forwardly across the bottom of the shank portion of the last at 88, crossing the portion 84, and thence the strip is manipulated to provide the forepart cross-straps 90 and 92, 5 the trailing end of the strip being secured at 94 to the bottom of the insole.

In Figs. 9 and 10 the outsole is indicated at 650 and the sock lining at 700. As already indicated, the outsole may be attached to the insole 10 by Goodyear stitching instead of by means of cement and such attachment of the outsole is indicated at 720.

In applying the strip which is to constitute the cross-straps it is not essential that the insole be 15 placed on a last and the strip wound around the insole and last as hereinbefore described, inasmuch as satisfactory results may be obtained by winding the strip or strips around an insole off the last so as to provide the desired cross-strap 20 structure (threading the strip or strips through the openings, if any, in the insole), and thereafter inserting the last so that it will be positioned relatively to the cross-strap structure as indicated in Fig. 4, thereby conforming the cross-straps to the contour of the last. Preferably the 25 opposite ends of the strip or strips would not be secured in place until after the last had been inserted thereby enabling the strip or strips to slip more or less through the openings in the 30 insole so that the various cross-strap loops may the more readily adjust themselves or be adjusted by the operator into conformity with the shape of the last. Finally the strip ends will be 35 pulled tight and secured in place so as to maintain the adjustment of the straps.

Having described our invention, what we claim as new and desire to secure by Letters Patent of the United States is:

1. That improvement in methods of making 40 sandals which consists in providing a series of open notches in the opposite edges of a sole, and winding a continuous strip of cross-strap material crosswise around the sole while entering portions of the strip laterally into said notches 45 to locate the successive portions of the strip so as to provide a series of cross-strap loops in desired locations at one side of the sole connected by a series of cross-stretches at the opposite side of the sole. 50

2. A sandal comprising an insole having a plurality of open notches in its opposite lateral edges, a continuous strip wound crosswise around the insole and extending through said notches, the portions of said strip at the upper side of the 55 insole being adapted to serve as cross-straps for holding the sandal on a foot, and an outsole fixedly secured to the insole and to the portions of said strip at the lower side of the insole.

3. A cross-strap sandal comprising an insole, 60 an outsole, a heel, forepart cross-straps connected by strips formed integrally therewith and extending crosswise between the soles, one of said strips being located in the vicinity of the ball line, cross-strapping at the heel of the sandal 65 including strips extending crosswise beneath the insole, one of said strips being located in the vicinity of the heel breast line, and a shank stiffener located between the soles and having one end portion interposed between said ball line 70 strip and the insole and the other end portion interposed between said heel breast line strip and the insole.

4. That improvement in methods of making 75 sandals which consists in winding a continuous

strip of cross-strap material a plurality of times around an insole thereby providing a plurality of cross-strap loops at the upper side of the sole and a series of cross-stretches integrally connecting said loops at the lower side of the sole, inserting a last between said loops and the insole and conforming the loops to the contour of the last, securing the ends of said strip in place by temporary fastenings, cementing said strip to the insole, removing said fastenings, and attaching an outsole.

5. That improvement in methods of making sandals which consists in providing a series of open notches in the opposite edges of an insole, 10 placing the insole upon a last, winding a continuous strip of cross-strap material crosswise around the insole and the last while entering portions of the strip laterally into said notches to locate successive portions of the strip so as 15 to provide a series of cross-strap loops in desired locations at one side of the insole connected by a series of cross-stretches at the opposite side of the insole, applying a stripe of cement to

the marginal portion of the lower side of the insole and to said cross-stretches of said strip, applying cement to an outsole, laying the outsole on the insole, and utilizing the cement on the outsole and the cement on the insole in cementing 5 attaching the outsole to the insole and in fixedly securing said strip to both soles.

6. That improvement in methods of making sandals which consists in providing a series of open notches in the opposite edges of an insole, 10 placing the insole upon a last, winding a continuous strip of cross-strap material crosswise around the insole and the last while entering portions of the strip laterally into said notches to locate successive portions of the strip so as 15 to provide a series of cross-strap loops in desired locations at one side of the sole connected by a series of cross-stretches at the opposite side of the sole, and attaching an outsole by cementing it to the insole and to said cross-stretches of 20 said strip.

WALTER I. GILLETTE.
ALBERT W. DUSSEAUXT.
